(57) **CLAIM**

The ornamental design for a pad for a creeper, as shown and
described.

DESCRIPTION

FIG. 1 is a top, right side, rear perspective view of a pad for a
creeper showing our new design;

FIG. 2 is a bottom, left side, front perspective view thereof;

FIG. 3 is a top plan view thereof;

FIG. 4 is a bottom plan view thereof;

FIG. 5 is a rear elevational view thereof;

FIG. 6 is a front elevational view thereof; and,

FIG. 7 is a right side elevational view thereof; the left side
being a mirror image thereof.
